SORTING APPARATUS FOR SUBSTANCES
OF DIFFERENT DENSITIES

François Jacques Barthélémy Berry, Lille, France

Application February 1, 1933, Serial No. 654,749
In France February 12, 1932

2 Claims. (Cl. 209—467)

The present invention relates to apparatus for the sorting of substances of different densities, and in particular for the removal of schist, and eventually the intermediate substances, from 5 coal, that is, the removal of the heavy and the partially heavy substances.

It relates particularly to improvements in apparatus of this class which consist of a shaking table with perforated bottom which is upwardly 0 traversed by a continuous current of air, whose action, combined with the shaking, serves to bring the heavy substances to the bottom part of the table from whence they can be evacuated through a suitable orifice, while the light parts, 5 that is, the screened coal, are discharged by overflowing from the upper part of the table.

According to the improvements in conformity with the invention, the table is connected, directly or by links, with rods driven at one end by a 10 common circular eccentric and separately suspended at the other end by arms pivotally mounted on the main frame. The connecting points of the table with the rods, are chosen in such a manner that the distances from these points to 15 the point of attachment of the rods with the eccentric are proportional to the lengths of the said rods.

In this manner, the inner end of each rod will 20 describe a circumference having the same radius as the eccentric, while the outer end of the rod will describe an arc of a circle whose radius is the length of the suspension arm. Thus the points situated between these ends will describe 25 closed trajectories whose form resembles that of an ellipse, in which the ratio between the large and the small axes will be greater according as such points come nearer the suspended end of the rod, and thus points can be found on said rods, 30 which will describe identical curves and with 35 synchronous motion.

If the shaking table is connected with such 40 intermediate points, it is evident that all points of this table will describe substantially elliptical 45 trajectories, each being the same as those of the several intermediate points on the arms.

The speed of the eccentric and the force of 50 the current of air will depend upon the size of the pieces of substance under treatment, and upon the differences in the density of the products, whether light, intermediate or heavy.

A form of construction of the sorting apparatus according to the invention is shown by way of 55 example in the accompanying drawing, in which:

Fig. 1 is an elevational view of the apparatus.

Fig. 2 is a diagram illustrating the operation of the apparatus.

The apparatus for sorting material of different densities shown in Fig. 1, essentially comprises a table with perforated bottom 10, adapted to hold, between its raised edges 11, the substances 12 to be sorted, these being fed by a suitably placed channel 13.

Below the said perforated bottom is mounted a hopper 14 which is connected by a yielding 10 bellows 15 with the discharge conduit 16 of an air fan 17 in continuous operation. A valve 18 serves to regulate the air blast which is thus delivered through the bottom 10.

The shaking table has at one end an orifice 15 25 for the discharge of the heavy substances, and at the other end, at the top part of the raised edge, is located a channel 26 for the discharge of the light substances. An orifice 27 situated laterally at the middle of one side of 20 the table, may be provided for the offtake of substances of medium weight.

At the top, the table is pivoted directly at 31, on each side 11, to a long rod 38 secured at one end to the strap 39 of an eccentric 40 keyed to 25 a rotatable shaft 41. The other end of the rod 38 is pivoted at 42 to a suspension arm 43 which is pivoted at 44 to the main frame.

Moreover, each side 11 of the table is connected by a link 45 to a point 46 on a rod 47, which is 30 shorter than the rod 38. Rod 47 is pivoted at one end to the eccentric strap 39 at the same point as the rod 38. The other end of rod 47 is connected at 48 to the free end of suspension link 49, which is pivoted at 50 to the main 35 frame. Arms or links 43 and 49 are identical in length and occupy parallel positions. The distances between the point of attachment of rods 38 and 47 to the eccentric strap 39 and the points 37 and 46 are positioned to the lengths 40 of arms 38 and 47, respectively.

The operation of the shaking table thus arranged is as follows:

It will be supposed that the material to be sorted such as raw coal, is supplied by the channel 13 of the shaking table. The fan 17 is set running, as well as the motor actuating each eccentric 40. It is observed that the points of rods 38 and 47 adjacent the eccentrics will describe complete circles whose radius is the radius of 50 the said eccentrics. On the contrary, the outer ends of said rods describe circular arcs whose radius is equal to the length of the arms 43 and 49, that is, substantially straight lines. In consequence, the intermediate points such as the 55

points 37 and 46 at which the table is attached to the rods 38 and 47, respectively, will move through closed trajectories whose form resembles that of an ellipse.

5 Due to the fact that the distances between the point of attachment of rods 38 and 47 to the eccentric strap and the points 37 and 46 are proportional to the lengths of rods 38 and 47, the trajectories described by points 37 and 46 are 10 similar to the trajectories described by all points of the table.

The shaking projects the substances upwardly, and the pieces which are partially impeded in their descent by the upward current of air will 15 be retarded in their fall according as they are lighter, so that the substances which drop again upon the perforated bottom will be situated according to their density.

However, the improvements according to the 20 present invention are particularly adapted, not only to sort, in the vertical direction, the substances supplied to the shaking table but also to direct such substances to their respective points of discharge, that is, the heavy substances to the orifice 25 and the light substances to the channel 26, and for this purpose, the current of air is given the necessary force, while the eccentrics 25 40 will have the required speed and stroke in order to comply with the operating conditions 30 to be further set forth with reference to Fig. 2.

It will be supposed (Fig. 3) that a point on the 35 perforated bottom 10 describes, as above stated, a trajectory of elliptical form in the direction of the arrow F, and that at a point A on this perforated bottom are located two particles of material, C of coal and S of schist; it will be observed that after the lighter coal particle C has attained a certain angular distance it will be projected according to the arrow F_c, while the schist particle 40 40 is projected at a later time according to the arrow F_s, so that the schist particle will be projected further to the right than the coal particle.

As all points of the shaking table describe the 45 same substantially elliptical trajectories, the action just described will take place at all points of the table, and thus the heavy pieces will have a general movement to the right, this movement taking place upon the whole length of the perforated bottom, so that tables of a great length 50 may be readily constructed, and will operate in a very regular manner.

This will form a veritable bed of schist against the orifice 25, and since this orifice is preferably arranged on the siphon principle, these pieces of 55 schist will only be discharged when a suitable

mass has been accumulated, and this obstructing bed will practically prevent all pieces of coal from passing through the schist.

From a practical standpoint, the respective movement of progression of the light and heavy substances are quite important, as this provides for an absolutely automatic separation of the substance, irrespectively of all irregularities in the feeding of the shaking table, and of the proportion of the light and heavy substances in the 10 raw material. In particular, supposing that no heavy substance is contained in the material supplied to the table, no particle will be brought to the orifice 25, and there will be no loss of material. 15

On the other hand, the substances of intermediate density will remain in position, without forward or backward motion, and will take a circular motion in the table.

Although such intermediate substances may be 20 in small proportion, they will finally fill up the table, so that it becomes necessary to discharge them through the lateral orifice 21. Alternately, it would be possible to evacuate such intermediate substances with the light substances, through 25 the orifice 26, then transporting such partly sorted material to a second shaking table which is adapted for the sorting of these intermediate substances. 30

I claim:

1. A sorting apparatus of the type described comprising a frame, a table having a perforated bottom, means for blowing air up through the perforated bottom, a rotating eccentric mounted in said frame, links pivoted to said frame, levers of unequal length connected to the ends of said links and connected together to the eccentric at one side of the latter, means connecting the table to the levers of unequal length, the distances between the points of attachment of the table to each lever and the points of attachment of each lever to the eccentric being proportional to the length of the respective levers. 35

2. Apparatus according to claim 1 comprising also an offtake for lighter material at one end of the table, an offtake for heavier material at the other end of the table, a baffle near the last-mentioned end extending downwardly through the layer of lighter material on the table, and an offtake located intermediate said ends of the 40 50 table and communicating with middle layers of the material on the table. 55
